SKIRT FORM

Monroe Jang, Merced, Calif.

Application July 13, 1953, Serial No. 367,448

2 Claims. (Cl. 223—95)

This invention relates to skirt forms and particularly to skirt forms which comprise a hanger for displaying women's skirts.

Women's skirts are customarily suspended from hangers of various kinds and in such a manner that they hang straight without suggesting the appearance of the skirt on a wearer. When skirts are suspended from hangers of this type the lines of the same naturally do not show and the weight of the material causes the same to hang straight.

It is an object of this invention to prepare a combination skirt form and hanger which permits one to hang the skirt for display purposes on a form which to some extent simulates the appearance of the same when worn.

It is a further object of this invention to provide a device of this kind which may be inexpensively produced.

It is a further object of this invention to provide a device of this kind which may be utilized without the use of pins or other fastening devices and which may be used by unskilled help and which may be used as a hanger and garment form and may be removed from the garment by the customer.

Other objects and advantages of this invention will appear from the following specification taken in conjunction with the accompanying drawings in which:

Figure 1 represents a plan view of a device incorporating my invention;

Figure 2 represents a cross-sectional detail taken along the line 2—2 of Figure 1.

Figure 3 illustrates one step in the method of positioning a garment with respect to my device preparatory to hanging it thereon; and

Figure 4 illustrates my device with a garment hung therefrom.

As illustrated in Figure 1 my device consists of a member 10 composed of cardboard or other semi-rigid material and is provided with substantially parallel top and bottom edges. The side edges 11 and 12 are formed, as indicated, in the shape of an open S to provide an upper narrow portion and a lower wider portion. At the narrowest portion a pair of notches 13 and 14 are provided which are adapted to receive a resilient member 16 formed of rubber or of some other elastic material which is adapted to surround both the form and any garment which is placed thereon.

A pair of orifices 17 and 18 accommodate a hook member 19, the upper end 21 of which is adapted to hang on a conventional rod and the lower end of which passes through the orifice 17 and forms a hook portion 22 which engages the member 10. It is apparent therefore that the member 19 may be readily removed from or at-

2

tached to the member 10 by clearing the hook portion 22 from the orifice 17 and then withdrawing the same through the orifice 18, for example.

When a skirt is to be hung upon my combination garment hanger and form, the form is placed generally as illustrated in Figure 3 with its upper edge near the top or waist of the skirt. The side portions of the skirt are then folded about the sides 11 and 12 and the member 16 snapped over the entire assembly. As illustrated in Figure 4 the skirt is hung in such a manner that the waist thereof is drawn in and that the remainder of the skirt flares out over the side edges 11 and 12 thereby simulating the form of a wearer.

It will be apparent from the foregoing that I have invented a garment form which is simple to use and which simulates the female figure sufficiently that a prospective purchaser may determine the probable appearance of the garment when worn.

I claim:

- 20 1. In a device of the character described adapted to display skirts, a flat plate-like form having curved sides forming an upper narrow portion and a lower wide portion, a notch formed in the narrow portion of each of said sides, stretchable means for surrounding the skirt and the form and adapted to engage said notches for holding the skirt to the form after the upper portion of the skirt has been folded around said form, said form having upper and lower openings and spaced equidistant from the sides of said form, a detachable hook having an upper curved portion and a lower bent portion, the portion of the hook intermediate the upper curved portion and the lower bent portion passing through the upper opening, and the lower bent portion engaging the top portion of said lower opening.
- 25 2. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
- 30 3. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
- 35 4. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
- 40 5. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
- 45 6. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
- 50 7. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
- 55 8. In a device of the character described adapted to display skirts, a flat plate-like form having curved sides defining an upper narrow portion and a lower wide portion, a notch formed in each of said sides at the narrow portion, stretchable means for surrounding the skirt and the form and adapted to engage said notches for holding the skirt to the form after the upper portion of the skirt has been folded around the sides of said form, said form having upper and lower vertical slots spaced equidistant from the sides of said form, a detachable hanger on said form and having an upper curved portion and a lower hook portion, the hook portion being at right angles to the upper curved portion, the position of the hanger being such that the portion of the hanger intermediate the upper curved portion and the lower hook portion passes through the upper slot and the lower hook portion engages the top portion of said lower opening, and an offset in the intermediate portion of said hanger, the curved portion of the hanger extending in a plane substantially parallel to the plane of the plate-like form and the lower portion of the hanger being inclined slightly from the plane of the plate-like form to permit the intermediate portion of the hanger to extend through the upper slot.
